UNITED STATES PATENT OFFICE

OTTO CLEMENS, OF BERLIN-CHARLOTTENBURG, GERMANY

CURB WITHOUT MOUTHPIECE

Application filed March 31, 1927, Serial No. 180,031, and in Germany April 3, 1926.

My invention relates to a curb without mouth-piece, in which when the reins are taken up the cheeks of the curb are simultaneously operating a nose-strap and a curb-chain 5 or chin-strap.

According to my invention I provide a hanger or suspending rod on each side of the head-stall preferably at both sides of a nose-band. Such hanger or suspending rod supports 10 pivotally the cheeks of the curb between their ends and a special nose-strap connected thereto as well as the curb-chain or chin-strap equally connected to the cheeks.

For the purpose of explaining my invention 15 some examples embodying the same have been shown in the accompanying drawings.

Fig. 1 shows a complete bridle comprising the curb without mouth-piece according to my invention, attached to a suitable head-20 stall, the reins being loose.

Fig. 2 is a similar view with the reins taken up.

Fig. 3 shows a cheek in a modified form.

Fig. 4 shows a cheek in another modification.

Fig. 5 shows a modified hanger with the cheek according to Fig. 3, pivotally attached thereto.

Fig. 6 is a front view of the hanger according to Fig. 5, the cheek not being shown.

A pair of hangers or suspending rods *b* made from any suitable material such as steel, nickel-alloy, brass or the like, is secured at each side to a head-stall, preferably by means 35 of a nose-band *a* connected in any usual or suitable manner to the cheek-piece *d* of the head-stall. The hangers *b* may be connected to the nose-band *a* by means of suitable holes or the like in the nose-band. At or near the 40 lower end of each hanger *b* the cheek *d* is pivotally secured at *r*. At or near the upper end of the cheeks *d*, a chin-chain *c* or a suitable chin-strap is attached. The reins *s* are connected to some suitable parts of the lower 45 ends of the cheeks *d* by means of rings or eyes.

A nose-strap *e* is connected with the hangers at *r* where the pivot for the cheek *d* is fixed to said hanger. When the reins are 50 taken up the cheeks are rocked around the

pivots *r*, a suitable traction being exerted both on the nose-strap *e* and the chin-chain *c*. By means of my device described above a suitable pressure may be put on the nose-strap *e* so that the rider or driver may exert 55 a very efficient influence on the horse. On the other hand, the entire bridle is very convenient to the horse, it fits perfectly without rubbing or unduly pressing the horse's sensitive parts of the head, and the objectionable mouth-piece is avoided.

In Fig. 3 a modified cheek *d*¹ is shown which is adapted to be secured to the hanger at *r* in the same manner as the cheek *d* in Figures 1 and 2. The cheek *d*¹ shown in Fig. 3 has a suitable hole *r*¹ for being pivotally attached to the hanger *b* and is provided with several rings *f*, *g*, *h* so that one or two reins may be attached to each cheek in a manner adapted to exert more or less pressure according to the sensitiveness of the horse. A hook *i*¹ is fixed to the upper part of the cheek *d*¹ and is made preferably integral with said cheek. The hook is adapted to carry the end of the chin-chain or the like. 75

In Fig. 4 another modification *d*² of a cheek-piece is shown, showing the general shape of the cheek of an S-curb. *r*² is a hole for pivotally securing a cheek *d*² to the hanger *b*. *m* is a ring for attaching the rein, substantially on the same level as the pivot *r*². *k* is another ring at the lower end of the cheek, to receive another rein. 80

A rein attached to the eye *f* (Fig. 3) or to the ring *m* (Fig. 4) is adapted to exert an 85 action upon the horse which may be compared with the action of a mild snaffle whereas the reins attached to the eyes *g* or *h* (Fig. 3) and *k* (Fig. 4), respectively, exert an action similar to the action of a curb. *i*¹ is a hook for the insertion of the end of a chin-chain or the like. 90

In Fig. 5 a modified form of a hanger *b*¹ is shown, the upper part *n* thereof being provided with an eye for connecting the hanger with the cheek-piece of the head-stall. In a front extension of the hanger *b*¹ another eye or slot *o* is provided for engagement with the nose-strap *e*¹. The axis of the slot or eye is inclined in respect to the axis of the hanger 95 100

b^1 to give a certain lift to the nose-strap e^1 and to prevent such nose-strap from slipping down on the nose of the horse.

5 A stud p projects from the surface of the hanger b^1 . r^3 is a pivot for the cheek d^3 , which, in the present example, is similar to the cheek d^1 shown in Fig. 3.

In Fig. 6 a front view of the hanger b^1 is shown with the cheek d^3 omitted. This figure 10 shows the stud p more clearly. Such stud p acts as a stop for the cheek d^3 when the reins are loose and the horse throws up its head. In such case the stud p will prevent reversing 15 of the cheek. When using the hanger shown in Figures 5 and 6 the nose-band a may be omitted.

While in describing the invention reference has been made to particular examples embodying the same I wish it to be understood that my invention is not limited to the 20 constructions shown in the drawings, and that various changes may be made in the general arrangement of the apparatus and the construction of its parts without departing 25 from the invention.

What I claim is:

1. A bitless curb comprising a head stall, a metal hanger plate having a pivot and removably attached to said head stall, a nose 30 strap removably attached to said hanger plate, a cheek-piece pivotally mounted on said pivot and having a fixed hook and rings integral therewith on opposite ends thereof and a chin-chain detachably engaging said fixed hook.

2. A bitless curb comprising a head stall, a metal hanger plate having a pivot and provided with an eyelet for removable attachment to said head stall and provided with a 40 second eyelet inclined to the axis of said hanger plate, a nose strap removably attached to said second eyelet, a cheek-piece pivotally mounted on said pivot and having a fixed hook and rings integral therewith on opposite 45 ends thereof and a chin-chain detachably engaging said fixed hook.

3. In a bitless curb, in combination, a head stall, a metal hanger plate having a pivot and provided with an eyelet for removable attachment to said head stall and provided with a second eyelet inclined to the axis of said hanger plate, a nose strap removably attached to said second eyelet, a cheek-piece pivotally mounted on said pivot and having a fixed 50 hook and rings integral therewith on opposite end thereof, said cheek-piece being integral with an eye adjacent to the pivotal axis thereof and a chin-chain detachably engaging said fixed hook.

60 In testimony whereof I have affixed my signature.

OTTO CLEMENS.
